UNITED STATES PATENT OFFICE.

ELMER F. WATERBOR, OF DETROIT, MICHIGAN, ASSIGNOR TO CHRISTINE McD. SIMPSON, OF DETROIT, MICHIGAN.

CAST-WHEEL CONSTRUCTION.

Application filed February 2, 1925. Serial No. 6,378.

To all whom it may concern:

Be it known that I, ELMER F. WATERBOR, a citizen of the United States of America, residing at Detroit, in the county of Wayne 5 and State of Michigan, have invented certain new and useful Improvements in Cast-Wheel Construction, of which the following is a specification, reference being had therein to the accompanying drawings.

- 10 The invention relates to cast wheel constructions and refers more particularly to cast malleable iron wheels, which are particularly applicable to motor vehicles. One of the objects of the invention is the provision of a cast wheel having spokes with a cross sectional contour, such that the parting line of the mould will not show from the front of the wheel. Another object is to so construct the spokes that the moulding of 15 the wheel will be simplified and at the same time the front surfaces of the spokes will be smooth. A further object is to provide a wheel of sturdy appearance and of great strength.
- 20 With this as well as other objects in view the invention resides in the novel features of construction and combinations and arrangements of parts as more fully herein-after set forth:
- 25 In the drawings:

Figure 1 is a side elevation of a portion of a cast metal wheel embodying my invention.

30 Figures 2, 3 and 4 are cross sections respectively on the lines 2—2, 3—3 and 4—4 of Figure 1.

The cast metal wheel is preferably formed of malleable iron and comprises, the hub section 1, the felly section 2 and the spoke 3 integral with and connecting the hub and felly sections. Each spoke is hollow throughout its length and also is of a general half round cross sectional contour, which progressively decreases in area radially outward from the hub section. The rear wall 4 of each spoke is substantially flat while the front wall 5 is substantially half round. This front wall beyond its point of mergence with the front and peripheral walls 6 and 7,

respectively, of the hub section 1 comprises 50 the converging arcuate wall sections 8 and 9, which at their front edges connect into each other and at their rear edges connect into the opposite edges of the rear wall 4. The front wall 5 at its point of mergence with the 55 front and peripheral walls of the hub section comprises the converging arcuate wall sections 8 and 9 and the intermediate wall section 10 therebetween, this intermediate wall section being substantially parallel to 60 the rear wall 4.

With this construction of spoke wherein the peripheral width thereof is greatest adjacent to the rear wall, I am enabled to cast the wheel so that the parting line does not 65 show on the front surface. Also moulding is simplified inasmuch as the largest portion of each spoke, which forms the front surface thereof, is in the drag of the mould so that I am enabled to use a shallow mould 70 cope and at the same time the front surface will be smoother than if located in the mould cope. Furthermore, the design is such that a wheel is provided having a sturdy appearance and great strength.

75 What I claim as my invention is:

1. A cast metal wheel including a hub section and spokes integral therewith and merging thereinto, said spokes at their points of mergence into said hub section having substantially parallel portions and arcuate portions merging into said parallel portions.

2. A cast metal wheel including a hub section and spokes integral therewith and merging thereinto, said spokes at their points of mergence into said hub section having substantially parallel portions and arcuate portions merging into said parallel portions and said spokes beyond their points of mergence into said hub section having a portion corresponding to one of said substantially parallel portions, and converging portions merging into said last mentioned portion and into each other.

95 In testimony whereof I affix my signature.

ELMER F. WATERBOR.
